UNITED STATES PATENT OFFICE.

WALTER D'ARCY RYAN, OF SCHENECTADY, NEW YORK.

DESIGN FOR A COMBINED HEADLIGHT HOUSING AND LENS.

Application filed April 21, 1926. Serial No. 17,370. Term of patent 14 years.

To all whom it may concern:

Be it known that I, WALTER D'ARCY RYAN, a citizen of the United States, residing at Schenectady, in the county of Schenectady and State of New York, have invented a new, original, and ornamental Design for a Combined Headlight Housing and Lens, of which the following is a specification, reference being had to the accompanying drawing, forming part thereof.

In the drawing:

Figure 1 is a side elevation of my ornamental combined headlight housing and lens;

Figure 2 is a front view thereof; and
Figure 3 is a rear view thereof.

I claim:

The ornamental design for a combined headlight housing and lens as shown.

In witness whereof, I hereunto subscribe my name, this 17th day of April, 1926.

WALTER D'ARCY RYAN.
